UNITED STATES PATENT OFFICE.

JOHN A. FLOOD, OF MINNEAPOLIS, MINNESOTA, ASSIGNOR TO NORTHWESTERN REED AND RATTAN COMPANY, OF MINNEAPOLIS, MINNESOTA.

MACHINE FOR FILLING CUSHIONS.

Application filed March 23, 1921. Serial No. 454,618.

To all whom it may concern:

Be it known that I, JOHN A. FLOOD, a citizen of the United States, residing at Minneapolis, county of Hennepin, and State 5 of Minnesota, have invented a new and useful Improvement in Machines for Filling Cushions, of which the following is a specification.

My invention relates to cushion stuffing machines and has for its object to provide 10 a device of this kind in which a great quantity of padding may be tightly compressed and stuffed within the cover of the cushion so that the padding will be uniformly laid 15 to give a smooth and full appearance to the cushion after the same is completed.

Another object of the invention is to provide means whereby the operation of the device may be expeditiously performed.

20 Another object of the invention is to provide means whereby the size of the cushion and padding applied thereto may be quickly and effectively varied at will.

A still further object of the invention is 25 to provide a table in conjunction with the cushion stuffing mechanism on which the same is mounted which may be used for holding the raw material required in the operation of the device.

30 In carrying out my invention I provide a table or bench on which the entire mechanism is mounted with a removable shelf positioned over a portion of the operating mechanism to expose principally the receptacle in which the padding is placed when the cushion is being stuffed and the operating levers necessary for manipulating the mechanism. I form the receptacle for the padding with a pair of hinged doors adapted 35 to be forced together by an arm to highly compress the padding prior to being inserted within the cushion. I further provide the receptacle in two sections with means for adjustably moving the sections with the doors hinged thereto relative to each other 40 so as to vary the width of the receptacle.

The full objects and advantages of my invention will appear in connection with the detailed description thereof and are particularly pointed out in the claims.

50 In the drawings, illustrating the application of my invention in one form:—

Figure 1 is a perspective view of my invention.

Figure 2 is a plan view of a portion of 55 the invention shown in Figure 1.

Figure 3 is a front elevational view of my invention with part shown in section.

Figure 4 is a vertical sectional view of the device taken on line 4—4 of Figure 2. 60

The structure upon which my invention is mounted comprises principally a bench or flat table 10 having a top 11 and six legs 12, 13, 14, 15, 16 and 17 rigidly secured to rails 18 and 19 on which said top 11 is supported. 65 A shelf 20 is secured to legs 12, 13, 14 and 15 below the top 11 and provides a space for storing the raw material used in the manufacture of the cushions.

At the forward end of table 10 towards 70 the left hand side is mounted a padding receptacle indicated at 21 which projects out beyond the table and over which a cushion cover 22 may be drawn as indicated in Figure 2. The padding is first placed 75 within the receptacle 21 and after the cushion cover has been drawn over the same said cushion padding is forced into the cover and both the cover and cushion padding discharged from the device in a manner to be 80 presently described.

Member 21, as best indicated in Figures 1 and 3, comprises a pair of enclosure members 24 and 25 formed of sheet iron, which members are bent so as to provide vertical sides 85 26 and 27 and bottoms 28 and 29. The upper portions of the sides 27 and 28 are secured to angle brackets 30 and 31 which are slidably mounted on the table top 11. These brackets have pairs of depending U-shaped lugs 32 and 33 secured to the same which are adapted to pass through vertical slots 34 and 35 in the top 11. Members 32 and 33 serve as guides for the sections 24 and 25 of the device by means of which 90 said sections may be advanced towards each other or away from each other to vary the width of the cushion at will. Beneath the table top 11 is positioned a shaft 36 which is journaled at one end in a bearing 37 100 secured to the underside of top 11 and at its other end in a bearing 38 fastened to the rail 19. This shaft is provided with right hand threads 39 at one end and left hand

threads 40 at the other end, which threaded portions of said shaft are adapted to screw into the respective depending U-shaped lug members 32 and 33 attached to the brackets 30 and 31. By rotating shaft 36 in either direction the members 24 and 25 of the cushion stuffing portion of my invention may be moved towards or away from each other at will. For manipulating shaft 36 I provide a hand wheel 41 which has a handle 42 secured thereto. Handle 42, as indicated in Figure 1, is positioned outside of the rail 19 where said handle may be easily operated by the user of the machine. It can hence be clearly seen that with the bottoms 29 and 28 of the cushion stuffing device overlapping each other as indicated in Figure 3, a continuous bottom is formed which may be varied in width as desired.

Hinged to the top of the side members 25 and 26 of the padding receptacle are two covers 43 and 44 which may be opened up to permit an insertion of the padding within the device or which may be closed as indicated in Figure 3 to completely encase the material on four sides. In the form of cushion which I usually construct I provide a plurality of springs 45 which are usually covered with some suitable fabric and come in a single unit and a padding 46 extending completely around said spring members on all sides thereof. This padding may be of cotton batting or other suitable material and is placed around the spring unit 45 as the same is inserted into the padding receptacle 21. In order to make a well padded cushion a sufficient amount of padding 46 is placed around springs 45 so that when the covers 44 and 43 are closed down upon the same, said covers exert a pressure upon the entire padding and springs within the member 21 thereby tightly packing the same.

To force the covers 43 and 44 in closed position upon the padding within the device and to hold said covers in their clamping positions I provide a device best shown in Figures 3 and 2. A lever 47 is pivoted at one end to a casting 48 secured to a rail 49 which is attached to legs 17 and 15 of the table 10. Lever 47 extends obliquely across the underside of the left hand portion of table 10 and protrudes through a slotted plate 50 attached to leg 16 which plate is provided with a number of hooks 51 adapted to engage and hold the said lever 47 in a number of vertical positions. Between plate 50 and the casting 48 is pivoted to lever 47 a swivel head 52 in which is rotatably mounted a rod 53 extending upwardly through a guide 54 secured to the table top 11. Rod 53 is provided with an arm 55 which has a depending portion 56 to which is pivotally connected a flat plate 57. Plate 57 is adapted to be positioned over the two closure members 44 and 43 of the padding

receptacle 21 and to force said members downwardly to compress the padding within the device as the lever 47 is forced downwardly by means of a handle 58 formed at the end thereof. When closure members 43 and 44 have been sufficiently depressed lever 47 is swung into engagement with one of the notches 51 to securely hold the device in place while the other operations performed upon the cushion take place. When the lever 47 is released from engagement with notches 51 the same including the plate 57 are raised above the device by means of a coil spring 59 attached to said lever and to a portion of the rail 18. When it is desired to open the hinged doors 43 and 44, the arm 55 is swung towards the side as indicated in dotted lines in Figure 2 where the same is out of the way. In this manner it can be clearly seen that the portion of the invention 21 adapted to receive the padding can be opened to permit the padding to be placed within the same and can thereafter be tightly closed to compress the padding within it.

After the padding has been placed in member 21 the cover of a cushion such as indicated at 22 in Figure 2 is slipped over the protruding end of member 21 and the padding within said member forced outwardly to cause the same to occupy the extreme end of said cover member and to gradually force said cover member off from the padding receptacle 21 so that when the cushion is completely ejected from the member 21, cover member 22 has been completely removed and the padding within the same occupies the entire space.

The device for causing the ejection of the cushion comprises primarily a plunger 259 which is secured to a beam 60 slidably mounted between two guide members 61 and 62 secured to the table top 11. Plunger 259 is adapted to pass between the portion 43-44 and 29-28 of member 21 and is of a width less than the smallest size to which this member 21 can be formed so that said plunger is at all times in a position to operate upon the cushion within said member. For actuating plunger 259 I provide a rope or cable 63 which is attached to a depending arm 64 secured to the underside of beam 60 and which operates in a slot 65 formed in the table 11. Cable 63 follows along the underside of table 11 parallel to the beam 60 and at a point adjacent the beginning of the member 21 passes over a pulley 66 and from thence it passes obliquely to and over another pulley 67 after which it extends downwardly and is secured to a foot operated treadle 68. Treadle 68 is secured by means of a hinge 69 to a rail 70 supported on legs 15 and 17 as will be noted in Figure 4. As said treadle is depressed by placing the foot on the same,

beam 60 together with the plunger 59 is caused to travel forward this bearing against the end of the spring 45 and padding 46 placed around the same, causing 5 both of these cushion members to be projected into the cover 22 as previously specified. Extending rearwardly from the depending arms 64 I provide another rope or cable 71 which passes over a pulley 72 mounted on the underside of table 11 which has attached to it a counter-weight 73 normally positioned close to the floor. As 10 plunger 59 is manipulated to eject the cushion within member 21 weight 73 is lifted to its position shown in dotted lines in Figure 4 and upon releasing the treadle 68, said weight 73 causes beam 60 and plunger 59 attached thereto to be returned to its normal position. In this manner the device is 15 caused to reset itself to its normal position leaving the member 21 empty and ready to be refilled with another cushion.

To cover up the plunger 59 and the operating mechanism therefor I provide a shelf 25 74 which is supported above the beam 60 and the guide members 61 and 62 by means of three walls 75, 76 and 77 to which the same is attached. This shelf forms a place where the raw material used for constructing the 30 cushion may be placed before the same is incorporated into the cushion and said shelf may be readily removed when access to the working parts of the plunger is desired.

The advantages of my invention are manifest. The device is exceedingly simple in construction and is very effective and positive in action. A great amount of padding can be placed around the spring members inserted into the cushion and the same force 35 within the cover member of the cushion so that the cushion has a smooth and uniform surface and still be well filled out and suitably padded. A man can operate this device at a high rate of speed turning out a 40 great many more cushions than he could otherwise have done by hand.

In accordance with the patent statutes I have described the principles of operation 50 of my invention, together with the apparatus which I now consider to represent the best embodiment thereof, but I desire to have it understood that the construction shown is only illustrative and that the invention can be carried out by other means and applied 55 to uses other than those above set forth within the scope of the following claims.

I claim:

1. A stuffing machine comprising a cushion receptacle, said receptacle being positioned in fixed relation to the machine, hinged closure members connected to said receptacle, a horizontal arm adapted to swing over and above said cushion receptacle, a plate connected to said arm and adapted to engage said closure members and

means for drawing said arm and plate downward to compress the stuffing within said receptacle.

2. A stuffing machine comprising a cushion receptacle, said receptacle being positioned in fixed relation to the machine, hinged closure members connected to said receptacle, a horizontal arm adapted to swing over and above said cushion receptacle, a plate connected to said arm and adapted to engage said closure members, a vertical shank formed on said arm pivotally and slidably mounted relative to said receptacle and a lever connected to the lower end of said shank for forcing the same 75 downwardly to compress the stuffing within said receptacle.

3. A stuffing machine comprising a cushion receptacle, said receptacle being positioned in fixed relation to the machine, hinged closure members connected to said receptacle, a horizontal arm adapted to swing over and above said cushion receptacle, a plate connected to said arm and adapted to engage said closure members, a vertical shank formed on said arm pivotally and slidably mounted relative to said receptacle and a lever connected to the lower end of said shank for forcing the same 80 downwardly to compress the stuffing within 85 said receptacle, and means for locking said receptacle, and means for locking said lever in clamping position.

4. A cushion stuffing machine including a padding receptacle open at its top adapted to receive the padding therethrough, a pair 100 of hinged closure members adapted to close said open top, a pivoted arm adapted to swing to the side of and above said hinged closure members, a plate on said arm adapted to engage said closure members, and means for forcing said arm downwardly to compress the padding within the receptacle.

5. A cushion stuffing machine including a padding receptacle, open at its top adapted to receive the padding therethrough, a pair 110 of hinged closure members adapted to close said open top, a pivoted arm adapted to swing away from and over said hinged closure members, a plate on said arm adapted to engage said closure members, and a lever 115 for forcing said arm against said closure members.

6. A cushion stuffing machine including a padding receptacle open at its top adapted to receive the padding therethrough, a pair of 120 hinged closure members adapted to close said open top, a pivoted arm adapted to swing away from and over said hinged closure members, a plate on said arm adapted to engage said closure members, a lever for forcing said arm against said closure members and means for locking said lever in the compressing position of said plate.

In testimony whereof I affix my signature.
JOHN A. FLOOD,
